United States Patent Office.

ALBERT CUNNINGHAM AND ALONZO SHARP, OF SALEM, OHIO.

Letters Patent No. 66,222, dated July 2, 1867.

IMPROVED POWER-HAMMER.

The Schedule referred to in these Letters Patent and making part of the same.

TO ALL WHOM IT MAY CONCERN:

Be it known that we, A. CUNNINGHAM and A. SHARP, of Salem, in the county of Columbiana, and State of Ohio, have invented certain new and useful improvements in Power-Hammers; and we do hereby declare that the following is a full and complete description of the same, reference being had to the accompanying drawings, making a part of this specification, in which—

Figure 1 is a side view of the hammer.

Figure 2, a rear end view.

Figure 3, a top view.

Figure 4, a front view.

Like letters refer to like parts in the different views.

A, fig. 1, is the bed-plate of the hammer, from which project the stays B, between the cheeks of which is mounted a pulley, C, upon the shaft D journalled in the stay, as shown in the drawing. On the inner end of the shaft is keyed a crank-wheel, E, the purpose of which will hereafter be shown. F, fig. 1, is a standard, in the upper part of which is cut a slot, G, (figs. 2 and 3,) to which is fitted a lug, H, and secured in the slot by a pair of washers, I. Immediately below the lower end of the slot is a lug, J, through which passes the rod K, which also passes through the adjustable lug H. At the upper end of the rod is placed a collar, L, between which and the adjustable lug H is a spiral spring, M. N is also a spring placed between the lug H and the collar O. By these two springs acting reversely to each other against the opposite side of the adjustable lug H, the rod and hammer P are kept at the same relative distance from the adjustable lug H. Thus, should the end of the hammer be forced upward, the spring N will bring it down again. On the contrary, should the rod and hammer be forced downward, the spring M will bring it back. Also, should the lug H be moved upward and downward in the slot, the rod and hammer will be carried with it in either direction. Q, fig. 2, is a slotted segment, the end, Q', of which is connected to the crank-wheel by a link, R, and the opposite end connects with a lever, R', by a link, S. Through the slot in the segment referred to projects the end S' of the lug H, and by which the hammer is operated as follows, viz:

On turning the crank-wheel to which the end of the segment arm is connected, it will be evident that in so doing the end Q' of the segment will be given a vertical reciprocating movement, whereas the opposite end X connected to the lever will remain stationary, it being the centre of the movement of the segment. As the segment moves upward and downward, it will give to the rod and hammer the same vertical reciprocal movement by means of the end or pin of the lug H embraced in the slot, the length of the stroke of the hammer being more or less as the pin is moved nearer to or from the centre X, and which is effected by the lever R'. This lever, as above said, is connected to the X end of the segment, hence by depressing the end of the lever will cause the segment to slide forward and thus bring the pin close to the centre of vibration, and thereby lessen the length of the strokes of the hammer, and so on reversing the direction of the lever, will throw the segment back more or less, and therefore will lengthen the stroke as the distance may be.

Power-hammers as usually constructed have no means of regulating the length of the stroke, hence the blows given are always of equal force, whether rapidly or slowly given. It is often desirable that the blows should be given quickly and at the same time lightly, as the nature of the work is such as to make it necessary to handle it in the least possible time. With the ordinary power-hammer this cannot be done, as the blows are given with the same force when given slowly as when made in quick succession. With the hammer above described this difficulty is obviated, as the length of the stroke can be easily controlled by the lever R', which is conveniently close to the hand of the operator, and thus he can increase or lessen the length of the stroke, as the case may be, without stopping or checking the speed with which the blows are given. The collars L O are so placed on the rod as to admit of their being brought nearer to or moved away from the lug H, and are retained in position by the pin P', thereby increasing or diminishing the tension of the springs M N. By this it is obvious that on adjusting the collars so as to bring them closer to the lug H, the tension of the springs will be accordingly increased, and will thereby increase the effective force of the blow given by the hammer P. By this means the force of the blow can be easily graduated to any desired degree, at the same time increasing or

diminishing the length of the stroke by the lever R', thus placing the length of the stroke and the effective force of the same immediately under the control of the operator.

What I claim as my improvement, and desire to secure by Letters Patent, is—

1. The links R S, lever R', and slotted segment Q, as arranged, in combination with the lug H, for the purpose and in the manner as set forth.
2. The adjustable collars L O, springs M N, in combination with the rod K and adjustable lug H, as and for the purpose herein described.

**ALBERT CUNNINGHAM,
ALONZO SHARP.**
